UNITED STATES PATENT OFFICE

ANDREW H. GRAVES, OF ARKANSAS CITY, KANSAS

SHIPPING CASE

Application filed April 1, 1929. Serial No. 351,710.

This invention relates to shipping cases of the folding type, and its general object is to provide a case of the above character that is primarily designed for eggs but can be made for other purposes, it being readily and easily assembled, and disassembled yet is rigidly held in assembled position, therefore casual collapsing thereof will be prevented.

Another object of the invention is to provide a shipping case of the folding type that is extremely light in weight and is sanitary and ventilated, with the result the contents thereof will be retained in a fresh condition for a maximum period of time.

A further object of the invention is to provide a case that includes a foldable partition, sides and ends, with a flanged bottom and top, the latter being entirely removable, but is capable of being securely fastened in operative position when the case is in its folded or set up positions.

A still further object of the invention is to provide a case of the character set forth, that is simple in construction, strong and sturdy, inexpensive to manufacture and is extremely efficient in operation and service.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:

Figure 1 is a perspective view of my case in assembled or set up position.

Figure 2 is a similar view thereof in folded position.

Figure 3 is a vertical sectional view taken longitudinally through the case.

Figure 4 is a sectional view taken approximately on line 4-4 of Figure 3, looking in the direction of the arrows.

Figure 5 is a sectional view taken approximately on line 5-5 of Figure 3, looking in the direction of the arrows.

Figure 6 is a view similar to Figure 5, with the case in folded position.

Figure 7 is a fragmentary perspective view showing the manner of detachably securing the end walls to the side walls when the case is in set up position.

Figure 8 is a similar view showing the manner of securing the partition in an upright position.

Referring to the drawings in detail, it will be noted that I have illustrated my case constructed in the form of an egg case, but I want it understood that it can be constructed in other forms for use for fruits and vegetables, as well as other commodities without departing from the spirit of the invention.

The reference numeral 1 indicates the bottom of the case as shown and the bottom has formed therewith side flanges 2 and end flanges 3 which have their ends secured together in any well known manner but I have illustrated tongues 4 formed with the ends of the side flanges and these tongues 4 are bent at right angles to the side flanges and fixed to the end flanges by solder.

It is to be understood however that other securing means such as rivets or the like may be used in the place of the solder.

The bottom which includes the flanges as above set forth is rectangular in shape, and the flanges have their upper ends downturned to provide beads 5. Secured to the bottom and following the shape thereof is a frame 6 formed from wire and this frame is braced by a longitudinally extending wire 7 and a transversely extending wire 8 which is looped about the longitudinally extending wire as at 9 and has its end portions looped about the side wires of the frame 6, as at 10. The end portions of the transversely extending wire 8 are vertically extended to provide uprights 11, and the frame 6 is secured to the bottom through the medium of substantially right angle members 12 formed from wire and which have their arms looped about the frame 6 at the corners thereof as best shown in Figure 4, with the juncture of the arms fixed to the bottom 1 by solder 13. The longitudinally extending wire 7 is likewise fixed to the bottom by solder and has its ends

looped about the ends of the frame 6 with uprights 14 formed therewith. The right angle members are likewise formed with uprights indicated by the reference numeral 15, 5 and the uprights 15 and 11 have their upper ends looped upon themselves and about the lower run of wire frames 16 of the side walls of the case.

The looped upper ends of the uprights 11 10 and side uprights 15 provide hinges whereby the side walls can be moved to their positions as shown in Figure 6, and the end walls also include wire frames which are indicated by the reference numeral 17 and have their lower 15 runs hingedly received by the end uprights 15 and the uprights 14. By this construction, it will be obvious that the side and end walls are capable of being folded as clearly shown in Figure 6 of the drawings.

20 The side and end walls also include wire mesh material which is of a shape to fit the frames as shown. The wire mesh material for the side walls is indicated by the reference numeral 18, while that of the end walls is indicated by the reference numeral 19.

The end walls are reinforced by spaced parallel wires 20 having their ends looped upon themselves, with one of the looped ends disposed about the outer run of the frame 17, while the other looped ends are disposed about the inner runs of the said frames 17. The side walls are likewise provided with reinforcing wires 21 arranged in spaced parallel relation with their ends looped about 35 the outer and inner runs of the side walls as suggested in Figure 3, and the side walls are further reinforced by strips of wire 22 arranged between the wires 21 and the end runs 23 of the frames 16.

40 The end walls have secured at their upper ends and at the sides thereof hook members 24 that have portions looped about the frames 17 and terminate in hooked ends 25 extending outwardly of the end walls for the purpose of receiving the end runs of the wire frames 16 as clearly shown in Figure 7. The wire mesh for the side walls is recessed at its ends as at 26 to accommodate the hooked ends 25. By this construction, it will be apparent 45 that when the hooked ends 25 are disposed in operative position, the side and end walls are held in a rigid upright position whereby casual collapsing or folding thereof will be prevented. A partition is provided 50 for the case as shown, and this partition includes a frame 27 that is of a shape to fit between the side walls as shown in Figure 3, but is foldable to lie upon the bottom 1, and for this purpose, the ends of the frame adjacent 55 the bottom are looped upon themselves around the transverse wire 8 as at 28, and the partition also includes bridging wires 29 that have their ends looped about the transverse wire 8 and the upper run of the 60 frame.

The spaced parallel wires of the end walls have secured between the same and adjacent the upper ends thereof eye members 30 that extend through the wire mesh of the end walls for a purpose which will be presently apparent, and formed with the end flanges of the bottom 1 are substantially U-shaped brackets 31 having ears which are soldered or otherwise fixed to the end flanges as suggested in Figure 3.

70 The top for the case is formed substantially like the bottom and is indicated by the reference numeral 32, with flanges 33 formed therewith and depending therefrom, the flanges being secured to each other by having tongues formed with the end flanges and being soldered to the side flanges.

75 The eye members 30 as well as the U-shaped brackets 31 provide keepers adapted to receive the hooked ends 34 of latches 35 that have one of their ends pivotally secured to the end flanges of the top and these latches include tongues 36 which provide finger pieces to operate the same as will be apparent. By this construction, the top can be secured to the 80 case when the latter is in its assembled position as shown in Figure 1, or when in its folded position as shown in Figure 2. The top and bottom are formed from galvanized iron or like metallic material and may be 85 corrugated if desired to add strength thereto.

90 From the above description and disclosure of the drawings, it will be obvious that I have provided a case in the form as shown that is primarily designed for 95 eggs and of course is adapted to receive the usual egg fillers and separating boards between the fillers upon opposite sides of the partition, and the case can be easily and readily assembled and disassembled but in any 100 event is constructed in a manner whereby it will stand much abuse without material damage thereto or its contents when arranged in its position as shown in Figure 1. The reinforcing wires 21 have secured to their upper 105 ends hook members 37 that include hooks 38 adapted to receive the frame 27 of the partition to hold the latter in its upright position 110 as shown in Figure 8.

115 By having the side and end walls hingedly secured as above set forth, it will be obvious that the walls are foldable and it is preferred when folding the case to arrange the partition which is likewise hingedly secured, on the bottom, then fold the end walls to their 120 positions as shown in Figure 6 and dispose the side walls in superposed position with respect to the end walls. The top is then secured in place through the medium of the latch and U-shape bracket 31.

125 While it has been stated that solder is used as a means for securing certain of the parts together, I want it understood that any means may be employed, or the parts may be electrically welded.

It is thought from the foregoing description that the advantages and novel features of my invention will be readily apparent.

I desire it to be understood that I may 5 make changes in the construction and in the combination and arrangement of the several parts, provided that such changes fall within the scope of the appended claims.

What I claim is:

- 10 1. A collapsible shipping case comprising a bottom having upstanding flanges, a bottom frame resting in said bottom, side and end frames received at their lower edges by the flanges, substantially right angle members secured to the bottom and having their ends looped about the bottom frame, transverse and longitudinal extending members having their ends looped about the bottom frame and extending upwardly therefrom 15 and looped about the lower rungs of the side and end frames to hinge and support the latter from the bottom frame, covering material secured to the side and end frames and 20 a cover carried by said side and end frames.
- 25 2. A collapsible shipping case comprising a bottom having upstanding flanges, a bottom frame resting in said bottom, side and end frames received at their lower edges by the flanges, substantially right angle members secured to the bottom and having their ends looped about the bottom frame, transverse and longitudinal extending members having their ends looped about the bottom frame and extending upwardly therefrom 30 and looped about the lower rungs of the side and end frames to hinge and support the latter from the bottom frame, covering material secured to the side and end frames, angular shaped members secured to the vertical and 35 longitudinal rungs of said end frames and extending outwardly to form hook shaped elements adapted to engage the vertical rungs of the side frames to detachably secure said side and end frames together, and a cover 40 45 carried by said side and end frames.

In testimony whereof I affix my signature.
ANDREW H. GRAVES.
